UNITED STATES PATENT OFFICE.

ALEXANDER HAMILTON, OF JOHNSTOWN, PENNSYLVANIA.

APPARATUS FOR REELING RODS.

SPECIFICATION forming part of Letters Patent No. 469,521, dated February 23, 1892.

Application filed May 1, 1890. Serial No. 350,246. (No model.)

To all whom it may concern:

Be it known that I, ALEXANDER HAMILTON, a citizen of the United States, residing at Johnstown, in the county of Cambria and State of Pennsylvania, have invented certain new and useful Improvements in Apparatus for Reeling Rods; and I do hereby declare the following to be a full, clear, and exact description of the invention, such as will enable others skilled in the art to which it appertains to make and use the same.

In the art of making rods of iron or steel of small sizes suitable for drawing into wire, or for other uses, it is found convenient to gather said rods into coils after said rods leave the rolls, or other devices which give them their proper size and form. For the purpose of gathering such rods into coils a reel is commonly used, and the object of my invention is to provide such a reel that the coiling process above referred to may be carried on in a speedy, economical, and convenient manner.

My invention relates to an improvement in reeling devices, whereby the end of a rod is automatically engaged by the spokes of a reel as it begins its motion, and in such a way that the rod is formed into a proper and convenient coil.

My apparatus consists of a suitable frame, of iron or other material, which frame carries in suitable bearings a hollow spindle, to which near its center is attached a driving-pulley to be driven by a belt or other device, and a brake-pulley to be acted on by a friction-brake, which may be of any suitable form, said spindle carrying at one end a disk and at the other end a collar, this latter serving to prevent too much lateral motion of said spindle. The disk above referred to may be made of cast or wrought iron. It has a hub bored out to receive the end of said hollow spindle, and a keyway corresponding to one in said spindle, so that disk and spindle may be keyed together, in order that said disk may receive its motion from the hollow spindle. This disk has radial arms which carry an annular plate of light wrought iron or steel, which annular plate serves to guide and to form the rods during the process of coiling.

In the disk and annular ring are inserted

and fastened a number of spokes or pins, the bases of said spokes forming a circle concentric with the disk, said pins having their axes perpendicular to the plane of said disk. 55

In the hollow spindle above referred to is a shaft, the axes of the shaft and spindle being the same. This shaft projects beyond the spindle at each end, one of its ends having a suitable clamp to prevent it from turning, the other end being provided with a keyway and thread and nut so formed as to hold in a fixed position near the center of the reel a device for automatically engaging the end of a rod and holding it for a short time while 65 the reel begins its revolutions. This device for receiving and engaging the end of the rod consists of a casting in the shape of a long box with openings in its ends, these openings having the form of a prismatic 70 wedge, the base of which is presented to the entering rod, and its sides forming guides to direct the end of the rod to its apex, where it is held for a moment while the spokes of the reel revolve. The parts of this device which 75 are subject to wear may be made removable.

Attached to the main frame are suitable bearings which carry a shaft, one end of which is provided with a lever so attached to the shaft as to cause by its motion a partial revolution of said shaft in either direction at the will of the operator. Attached firmly to and at right angles with the axis of this shaft are two arms which carry at their upper ends an idler pulley in proper bearings, and at another 85 part of said shaft is attached firmly a rocker-arm, which arm is connected with a device for moving a brake-block from or to the brake-pulley before mentioned. The construction of this shaft and its attachments is such that 90 an upward motion of the lever fastened at its end has the effect of moving the brake-block from contact with the brake-pulley and at the same time producing tension in a loose belt which runs on the belt-pulley before referred to, while a motion of the lever-handle in a downward direction allows said belt to become loose, and a continuation of the motion in a downward direction has the effect of causing the brake-block to come in contact 95 with the surface of the brake-pulley. A belt 100 from a shaft or counter-shaft driven by any

suitable power runs loosely about the belt-pulley, which pulley is attached to the hollow spindle before described in such a way that motion is imparted to the machine only when sufficient tension is produced in this belt by the pressure of the idler-pulley. The hand-lever above referred to may have a prolongation of suitable form to carry an adjustable counterpoise for the purpose of making it more easily moved.

Instead of placing my reel opposite finishing pass of rolls, with its axis parallel or nearly parallel to axes of rolls, I place it to one side with its axis perpendicular to the axes of rolls, as shown in Figure 5, and use a curved trough or guide for the rod, and my reels may also be placed with their axes forming an angle with the axes of the rolls. This construction has the advantage of enabling me to use two or more reels, when desired, and the partly straight and partly curved form of the guide which I use is found in practice to possess a great advantage over the straight form. As the overflow of the rod is governed by the curve it is not liable to occur near the reel nor the rolls, but only at the curve. The rod is not liable to kink or foul itself, and the feed of the rod to the reel is rendered more certain and perfectly automatic. As an additional assurance of these results, the part of the guide-trough which is in a line with the delivery and next to the rolls may be closed entirely, or may have clamps or guards over it upon its straight portion, which will insure the escape of the overflow to occur only from the curved portion of the trough. In either case the object which is attained is that when the rolls deliver a rod faster than its reel coils it, the surplus rod escapes over the side of the trough at a definite point—viz., upon the curved portion in the form of a U-shaped loop, one side of which is a prolongation of the original line of issue of the rod from the rolls.

The delivery of the rod to the reel might be effected by means of a uniform curved guide, which would be the form of construction most readily suggested; but this form would not enable me to control the overflow by giving it a definite form and making it occupy a definite space, which I aim to do and accomplish by the form of guide which I use.

Having given this general description of my invention, I will now, to make my invention more clear, refer to the annexed four sheets of drawings, which form a part of this specification, and in which like letters refer to like parts.

Fig. 1 is a front end elevation with part of the annular disk broken away to show parts behind it. Fig. 2 is a front side elevation with coiling-reel proper removed, showing the idler-pulley and device for receiving and engaging end of rod in vertical sections through their centers. Fig. 3 is a plan showing belt and brake-pulleys and cast-iron and wrought-iron disks of reel in horizontal sections

through their centers. Fig. 4 is a horizontal section of hollow spindle, showing contained shaft in plan and in place. Fig. 5 is a general plan showing rod-roll, carrying-trough for rod, and rod-reel. Fig. 6 shows an arrangement of two or more reels for alternate or simultaneous use. Fig. 7 is a front end elevation in outline showing a wire entering the reel and becoming hooked over one of the spokes.

In the different figures, A represents the frame having bearing-boxes $g g'$, with caps $a a'$, which caps are held down in place by the bolts and nuts $j j'$. The hollow spindle B rests in these bearing-boxes $g g'$, and said hollow spindle contains the shaft C.

b represents a collar on end of hollow spindle B, and d is a clamp made fast at one end to the shaft C by the set-screw f , and at its other end this clamp is made fast to frame A by means of bolt e . This clamp d thus prevents shaft C from turning or moving in any way.

At the end of the spindle B opposite that occupied by collar b is attached the disk L, to which is attached the annular disk M and the spokes $s s s$. It is upon these spokes s and against this plate M that the rods are coiled during the operation of the machine.

Resting upon the end of the hollow spindle B, against its shoulder k , is the device D for receiving and engaging the end of rod to be coiled. This device D is not fastened to hollow spindle B, but is keyed to shaft C by key k' and further held in place by nut n , so as to be immovable. This device D has a diagonal rib N and spring-plates $p p'$, so constructed as to form a wedge-shaped cavity, into which, in the course of operation, the end of the rod to be coiled enters suddenly and forcibly, with the effect of causing the spring-plates $p p'$ to pinch and hold end of said rod temporarily, while the spokes $s s s$, between two of which the rod enters, begin to revolve, causing the end of the rod to assume the form of a hook about one of the spokes and the rod to begin to coil upon the spokes. This device may also be made with solid plates, in place of spring-plates $p p'$ or in other suitable manner or form to produce the result desired, as specified.

The dark circle marked z on rib N is an oil-hole for the purpose of allowing the bearings between the hollow revoluble shaft B, the engaging device D, and the fixed bar C to be lubricated.

K is a belt-pulley fastened to the hollow spindle B, operated by a vertical belt which runs loosely under it, which belt is brought in contact with pulley K by the idler-pulley H.

I is a brake-pulley attached to the hollow spindle B.

F is a shaft carried by frame A in the bearing-boxes $h h'$. Attached to shaft F at one end is the lever O, which lever has a convenient handle at one end, its other end carrying a counter-weight E, which counter-weight may be so ad-

justed as to balance the other moving parts attached to shaft F. Attached firmly to shaft F are two rocker-arms l l', which carry at their upper ends the shaft G, which shaft carries 5 idler-pulley H, shaft and pulley being so fitted that pulley H can revolve easily about shaft G. Attached to shaft F is another rocker-arm o, which is so attached to a band q, carrying 10 brake-block r, that the motion of rocker-arm o in one direction causes the brake-block r to rub against the surface of brake-pulley I, while the motion of the same rocker-arm o in a contrary direction releases the brake-block from contact with surface of brake-pulley I. 15 The positions of brake-block r and idler-pulley H are so adjusted relative to shaft F, by the partial revolution of which both are actuated, that as the pulley is brought forward to produce tension in the belt and thus start the 20 machine, the brake-block r is released from contact with the brake-pulley, and vice versa. Thus by the movement of the lever O in a proper manner the reel may be started or stopped at the will of the operator.

25 Referring now to Fig. 5, v represents the rolls which deliver rod to be coiled to the trough m from groove in said rolls, designated by x. This trough m may be of any form suitable to hold and guide the moving rod in 30 its passage from rolls to reel. This trough is curved in plan and open in cross-section in such a way that should the finishing-rolls deliver the rod faster than the reel coils it the surplus rod may escape from the trough in 35 the form of a loop without crimping or kinking. As shown in Fig. 5, that part of the trough or guide end extending from the rolls to the point W may be closed, either wholly or by clamps placed upon it, so that the rod 40 cannot escape from it, while the curved part thence to the reel is open to allow the lateral escape of the rod. This closing of the trough or guide next to the rolls will be found useful in practice; but it is not essential, as very 45 good results are obtained from my curved form of guide without closing any part of the same.

Having now described my device, I will proceed to show how it is operated. In the 50 due course of operations a rod issues from the groove x in the roll v in such a way as to enter trough m. In its motion along this trough in the direction of the arrow shown in Fig. 5 it is supported by this trough and guided 55 to the reel, which is now stationary. The end of the rod passes between two of the spokes s s and enters the wedge-shaped cavity in the device D. At this instant the operator raises the lever O, thus bringing the belt, which is 60 always in motion, in contact with the face of the pulley K, which beginning to revolve, imparts its motion to the hollow spindle B, which in turn causes the disks L and M and their spokes to revolve also. This upward motion 65 of the lever also causes the brake-block r to

be removed from contact with surface of brake-pulley I, thus allowing above revolution to take place. The end of the rod now being in the wedge-shaped cavity in the device D, the revolution of the spokes s s s has 70 the effect of causing the end of said rod to become hooked about one of said spokes, and the motion of the reel continuing the rod is rapidly coiled upon the spokes.

Referring now to Fig 7, the dotted line 75 marked y' indicates the forward end of a rod as it is delivered to the reel. The disk M, which carries the spokes s s s, as viewed in this figure, is supposed to revolve in a right-hand direction. The heavy line represents 80 the wire as it becomes hooked over one of the spokes s during their revolution. The forward end of the hooked wire is marked w, and the back end is marked y. For convenience of illustration only a small portion of 85 the forward end of the rod is shown.

When the rod is all coiled on the spokes, the machine is stopped by moving lever O in a downward direction, thus releasing the tension of the belt on pulley K and applying 90 brake r to brake-pulley I. The coil of rod may now be removed by an attendant by pulling it over spokes s s s with a suitable pair of tongs or other device for taking hold of 95 said coil. This coil being removed the reel is ready for another operation.

What I claim as of my invention, and desire to secure by Letters Patent, is—

1. In a rod-reel, the combination of a hollow 100 revolvable spindle, a disk or wheel provided with a series of projecting pins upon which the rod is coiled, said disk or wheel being attached to said spindle, a fixed shaft contained in said spindle, and a fixed device for temporarily holding the end of a rod, which device is supported and held centrally by 105 said fixed shaft for the purpose of engaging the end of a rod to be coiled, substantially as set forth.

2. In a rod-reel, the combination, with the 110 frame and driving mechanism, of a hollow revolvable spindle, a disk or wheel provided with a series of projecting pins, said disk being carried by said spindle, a fixed bar passing through said spindle, a fixed device for 115 temporarily holding the end of a rod, which device is supported centrally and held on the end of said bar, and a clamp attached to said bar, substantially as set forth.

3. In a rod-reel, the combination, with the 120 frame and driving mechanism, of a hollow revolvable spindle, a disk or wheel provided with a series of projecting pins, said disk being carried by the spindle, a fixed bar extending through the spindle, and a device for 125 temporarily holding the end of a rod, which device is centrally fixed on said bar and which consists of a box-shaped casting with openings in the ends having the form of a prismatic wedge, the base of which is presented 130

to the entering rod and the sides of which form guides to direct the rod to its apex, substantially as set forth.

4. In a rod-reel, the combination, with the frame and driving mechanism, of a hollow revoluble spindle, a disk or wheel provided with a series of projecting pins, said disk being carried by said spindle, a fixed bar passing through said spindle, a device for temporarily holding the end of a rod, which device is centrally fixed on the end of said bar, said device having, in combination, a box-shaped forging or casting, a funnel or wedge shaped cavity therein, and a spring-plate for gripping the end of a rod, substantially as set forth.

5. In a rod-reel, the combination of a driving-pulley and brake-pulley with a hollow revoluble spindle upon which said pulleys are fastened, a disk or wheel provided with a series of projecting pins, said disk being carried by said spindle, a fixed shaft passing through said spindle, and a box-shaped forging or casting having a wedge-shaped cavity within its end to receive and grip the rod, substantially as set forth.

6. In a rod-mill, the combination, with the rolls, of a reel or reels placed at either or both sides of the delivery-line of the rolls, each of said reels having, in combination, a hollow revoluble spindle, a disk or wheel provided with a series of projecting pins, said disk being carried on said spindle, a fixed bar or shaft passing through said spindle, a fixed device for temporarily holding the end of a rod, said device being supported centrally by said bar and having the form of a box with a wedge-shaped opening at its end, one or more curved or partly-curved troughs to guide the rod to its reel, the straight end of said troughs being next to and in line of delivery of the rolls and at right angles to the axes of said rolls, and a clamp or clamps attached to and closing said trough in its straight portions for

the purpose of allowing the surplus of the rod to escape at a certain part of its curved portion, substantially as set forth.

7. In a rod-mill, the combination, with the rolls, of a reel or reels placed at either or both sides of the delivery-line of the rolls, each of said reels having, in combination with its frame and driving mechanism, a hollow revoluble spindle, a disk or wheel provided with a series of projecting pins, said disk being attached to said spindle, a fixed bar passing through said spindle, and a fixed device for temporarily holding the end of a rod attached centrally to said bar, with a trough or troughs to guide the rod from the rolls to the reel, which trough is partly opened and partly closed and which conforms to the line of delivery of the rolls in its closed section next the rolls and is open to admit of the overflow of the rod at a proper place near the reel, substantially as set forth.

8. In a rod-mill, one or more reels the axes of which are arranged perpendicularly to the axes of the rolls, each reel having, in combination with its frame and driving mechanism, a hollow revoluble spindle, a disk or wheel provided with a series of projecting pins and attached to said spindle, a fixed bar passing through said spindle, and a fixed device for temporarily holding the end of a rod, said device being held centrally by said bar, with a curved trough or troughs, said trough having curved and straight portions and being provided with an opening to allow the surplus rod to overflow and escape in the form of a loop at a certain place, substantially as set forth.

In testimony whereof I affix my signature in presence of two witnesses.

ALEXANDER HAMILTON.
